UNITED STATES PATENT OFFICE.

WALTER O. SNELLING, OF ALLENTOWN, PENNSYLVANIA, ASSIGNOR TO TROJAN POWDER COMPANY, OF NEW YORK, N. Y., A CORPORATION OF NEW YORK.

AMMONIUM-NITRATE EXPLOSIVE.

1,343,063.

Specification of Letters Patent. Patented June 8, 1920.

No Drawing.

Application filed January 14, 1919. Serial No. 271,175.

To all whom it may concern:

Be it known that I, WALTER O. SNELLING, a citizen of the United States and resident of Allentown, Lehigh county, Pennsylvania, have invented certain Improvements in Ammonium - Nitrate Explosives, of which the following is a specification.

My invention relates to ammonium nitrate explosives, and its object is the production of such an explosive of high brisance, and one which while having a relatively high ammonium nitrate content will not cake or become solid or rigid either during manufacture or after long storage. My invention further relates to ammonium nitrate explosives in which nitro-starch is employed, in relatively small amount, as a sensitizer.

Explosives containing ammonium nitrate and nitro-starch have heretofore been employed but in all such explosives previously made or suggested, either the ammonium nitrate has been a minor explosive constituent, present in amounts of 30% or 40% only, the primary explosive agent present being the nitro-starch, or a mixture of nitro-starch and an inorganic nitrate such as sodium nitrate, or else the explosive has been of the class known as ammonium nitrate metallic explosives in which a metal or metallic ingredient such as aluminum has been employed to raise the temperature of combustion and act as a quickening agent, and which explosives are used in compressed form. In my explosive, no metallic ingredient is employed, the explosive is in pulverulent form and remains so, and so far as I am aware I am the first to produce an ammonium nitrate - nitro - starch explosive of this type, in which the ammonium nitrate is the primary explosive present in relatively high content and the nitro-starch in relatively low content.

In mixtures of ammonium nitrate and nitro-starch, in which there is a high ammonium nitrate content, there is a tendency to set to a firm cake after standing for some time, as the result of a recrystallization of the ammonium nitrate, this recrystallization being due in part to a small initial moisture content of the ammonium nitrate and in part to small amounts of moisture taken up in the course of the manufacture of the explosive. This setting or caking decreases the sensitiveness of the explosive and in-

terferes with loading operations. I have discovered that if the ammonium nitrate crystals be coated with very finely divided particles of a pulverulent agent, the direct contact between the crystals and ammonium nitrate which is necessary before recrystallization and setting can occur, can be prevented.

Where the nitro-starch constitutes not less than approximately 20% of the mixture and is thoroughly mixed with the ammonium nitrate, constituting not less than approximately 50% of the mixture, the nitro-starch itself can act in the double capacity of a sensitizer and a pulverulent agent for maintaining separate the crystals or grains of ammonium nitrate and accordingly I have discovered that it is entirely practicable to produce ammonium nitrate - nitro - starch explosives with high ammonium nitrate content and relatively low nitro-starch content, and to produce and maintain said explosive in uncompressed pulverulent form.

With explosives made according to my present invention and using proportions of ammonium nitrate in excess of 50% of the total, and nitro starch in the proportion of less than 20% of the total, I find that it is desirable to add a further agent to assist in keeping apart the crystals of nitrate of ammonia and to prevent the mass setting or caking by the recrystallization of the ammonium nitrate. For this purpose I may use any pulverulent material of high covering power, such for example as powdered iron oxid (ochre or rouge). It will be understood that such added constituent of high covering power is explosively inert and that its sole function is the keeping apart of the crystals of nitrate of ammonia by coating them with very finely divided particles of the agent, and thus preventing that direct contact between the crystals which leads to setting or caking. Nitro-starch can act successfully as a sensitizing agent when present in as small an amount as 5% of the total quantity of the explosive, but in such case it is necessary, in order to prevent caking, to add the additional pulverulent agent in an amount constituting approximately 15% of the total mixture. The particles of nitro-starch and the additional pulverulent material are caused to be thoroughly interspersed among

the ammonium nitrate particles, and the direct adhesion of these particles to each other is thereby prevented.

5 An illustrative formula for nitro-starch explosive containing iron oxid for the purpose stated is the following:

10	Nitro-starch	12.0%
	Ammonium nitrate	60.0%
	Sodium nitrate	18.0%
	Hydrocarbon oil	2.0%
	Iron oxid (rouge)	8.0%
		100.0%

15 In making up explosives containing nitro-starch, ammonium nitrate and the finely divided covering material, other ingredients heretofore used in making up nitro-starch powders may be added, as illustrated in the 20 formula, and as will be readily understood, and the relative proportions of nitro-starch, ammonium nitrate and pulverulent ingredient can be varied within limits to produce explosives of the varying specific characteristics. I have obtained useful results with 25 mixtures employing nitro-starch from 5% to 20%, ammonium nitrate from 40% to 90%, and iron oxid from 2% to 15%, the percentages given being percentages of the entire explosive mixture.

Other finely divided materials of high covering power which I have successfully employed for the purpose stated, are powdered talc, and powdered silica. These 35 ingredients give a high degree of non-inflammability, and it will be understood that other equivalent finely divided inert material may be employed. Where absolute non-inflammability of the finished explosive is not necessary, I have found finely divided charcoal and ordinary starch to give satisfactory 40 results.

So far as I am aware, I am the first to discover that ammonium nitrate-nitro-starch 45 explosives can be made in which the ammonium nitrate is the primary explosive agent, and the explosive maintained in pulverulent form, and to discover that caking can be avoided by the coating of the ammonium 50 nitrate particles with a pulverulent agent, either the nitro-starch itself, when present in an amount as great as 20% or more, or the nitro-starch and an additional inert pul-

verulent material, when the nitro-starch constitutes less than 20% of the entire mixture.

I claim:

1. An explosive containing ammonium nitrate in excess of 40% of the entire mixture, nitro-starch and a finely divided material of high covering power interspersed among the particles of said ammonium nitrate.

2. An explosive containing ammonium nitrate, constituting from 40% to 90% of the entire mixture, nitro-starch, and a finely divided material of high covering power interspersed among the particles of said ammonium nitrate.

3. An explosive in non-caked pulverulent form containing nitro-starch 5% to 20% and ammonium nitrate from 40% to 90% of the entire mixture.

4. An explosive in non-caked pulverulent form containing nitro-starch 5% to 20% and ammonium nitrate from 40% to 90% of the entire mixture, and a finely divided material of high covering power interspersed among the particles of said ammonium nitrate.

5. An explosive containing nitro-starch 5% to 20%, ammonium nitrate from 40% to 90% of the entire mixture, and an additional finely divided material of high covering power interspersed among the particles of said ammonium nitrate, said finely divided material comprising 2% to 15% of the entire explosive.

6. An explosive containing ammonium nitrate constituting from 40% to 90% of the entire mixture, nitro-starch and powdered iron oxid interspersed among the particles of said ammonium nitrate.

7. An explosive containing ammonium nitrate 40% to 90% of the entire mixture, nitro-starch 5% to 20%, and powdered iron oxid interspersed among the particles of said ammonium nitrate.

8. An explosive containing ammonium nitrate 40% to 90% of the entire mixture, nitro-starch from 5% to 20%, and powdered iron oxid thoroughly mixed with said ammonium nitrate, said iron oxid comprising 2% to 15% of the entire explosive.

9. An explosive comprising ammonium nitrate 60%, nitro-starch 12%, sodium nitrate 18%, hydrocarbon oil 2% and iron oxid 8%. 105

WALTER O. SNELLING.
